UNITED STATES PATENT OFFICE.

HARRY C. WILSON, OF NEW YORK, N. Y.

ADJUSTABLE SLEEVE-CHART.

SPECIFICATION forming part of Letters Patent No. 690,214, dated December 31, 1901.

Application filed September 25, 1901. Serial No. 76,493. (No model.)

To all whom it may concern:

Be it known that I, HARRY C. WILSON, a citizen of the United States, and a resident of the city of New York, borough of Manhattan, 5 in the county and State of New York, have invented a new and Improved Sleeve-Pattern, of which the following is a full, clear, and exact description.

This invention relates to improvements in 10 patterns for sleeves of garments—such as dresses, coats, and the like—and the object is to provide a pattern of this character that may be quickly and easily adjusted to the desired measurements.

15 I will describe a sleeve-pattern embodying my invention and then point out the novel features in the appended claims.

Reference is to be had to the accompanying drawings, forming a part of this specification, 20 in which similar characters of reference indicate corresponding parts in all the figures.

Figure 1 is a front view of a sleeve-pattern embodying my invention. Fig. 2 is a back view thereof; and Fig. 3 is a section on the 25 line xx of Fig. 2, but drawn on a larger scale.

The sleeve-pattern comprises a curved top piece 20, having two pins 21 22 near its opposite ends, of which the former engages a curved slot 23 in the upper arm-piece 24.

30 This upper arm-piece has a pin 25 engaging a slot 26 in the shoulder-piece 27, which has a downwardly-extended arm 28, corresponding to the upper arm-piece 24. The pin 22 of the top piece 20 passes through the shoulder-piece 27 and engages in a slot 29 in an extension shoulder-piece 30, which extends downward under the forward arm-piece 28 of the shoulder-piece 27 and is adapted to form a part of the outline of the sleeve-pattern. Be-

40 low said extension shoulder-piece is arranged the elbow-piece 31, provided with slots 32, engaged by pins 33 34, of which the former are fastened to the shoulder-piece 27, while the latter are fastened to the extension shoulder-piece 30 and engage horizontal slots 35 in the shoulder-piece. The two slots 32 converge toward their lower ends, so that when the elbow-piece 31 is shoved in or out the pins 34 will be caused to travel toward and 45 from the pins 33, thereby keeping the outline of the extension shoulder-piece 30 in register with the outline of the elbow-piece 31.

With the upper arm-piece 24 is connected, by pins 36 engaging a slot 37, a second elbow-piece 38. The lower arm-piece 39 is connected 55 with the elbow-piece 38 by pins 40 engaging in a slot 41. The pins are here shown as connected to the part 38, and the slot is formed in the part 39. With the elbow-piece 31 another lower arm-piece 42 is connected by pins 60 43 44, the pin 43 operating in a slot 45 in the part 42, while the pin 44 operates in a slot 46 in the part 31. This lower arm-piece 42 has a bottom member 47 projecting approximately at right angles therefrom and provided with a slot 48, engaged by pins 49 upon a cuff-piece 50, which is pivotally connected with the lower end of the lower arm-piece 38 by a pin 51.

This sleeve-pattern is so constructed as to 70 give upon its outside the pattern of the top part of the sleeve and with its inner outline the pattern of the under part of the sleeve. Along the curved lower edge of the shoulder-piece 27 is located a graduation 52, and at the 75 junction of the upper arm-pieces 24 and 28 with the elbow-pieces 31 and 38 are located corresponding graduations 53. A similar graduation 54 is located at the junction of the parts 31 and 42, and a cuff-graduation 55 is 80 located at the lower edge of the part 47.

The sleeve-pattern is set at the top by moving the upper arm-piece until it indicates the proper number on the graduation 52, as indicated by the size around the arm. Then the 85 elbow-pieces 31 and 38 are moved up or down until they indicate the same number on the graduations 53, this adjustment being made according to the size above the elbow. Then the lower arm-pieces 39 and 42 are adjusted 90 according to the size below the elbow, as indicated by the graduation 54, and finally the cuff-piece is adjusted on the graduation 55 according to the cuff-measure. All the other parts follow the various adjustments, and at 95 the same time, as described, the extension shoulder-piece always remains with its outline in registry with the outer edge of the elbow-piece with which it connects.

Having thus described my invention, I 100 claim as new and desire to secure by Letters Patent—

1. A sleeve-pattern provided with a shoulder-piece and an extension shoulder-piece

which overlap lengthwise, an elbow-piece, the upper end of which is lapped by the extension shoulder-piece, said elbow-piece having a slot parallel with the inner edge of the elbow-piece 5 and an oblique slot at the angle thereof parallel with the outer edge of the elbow-piece, and the shoulder-piece being provided with transverse slots crossing said oblique slot, pins secured to the extension shoulder-piece 10 in a line parallel with the outer edge of said extension shoulder-piece, said pins passing through the transverse slots of the shoulder-piece and through the oblique slot of the elbow-piece, another set of pins secured to the shoulder-piece in a line parallel with the inner edge of said shoulder-piece, said pins engaging the other slot of the elbow-piece, and 15 adjustable parts connecting the upper end of the elbow-piece with the lower end of the shoulder-piece and completing the outline of the pattern, substantially as specified.

2. A sleeve-pattern, consisting of an elbow-piece an upper arm-piece adjustably secured to the elbow-piece, a shoulder-piece to which

the upper end of the arm-piece is adjustably 25 secured, said shoulder-piece having an arm portion, a curved top piece adjustably secured to the arm-piece and having its upper end pivoted to the shoulder-piece, an extension shoulder-piece having an arm portion and adjustably secured to the body and arm portions 30 of the shoulder-piece, a second elbow-piece adjustably secured to the arm portions of the shoulder and extension shoulder-pieces, a lower arm-piece adjustably secured to the 35 elbow-pieces, one of said arm-pieces being provided with an annular extension at its bottom, and a cuff-piece pivoted to one of the arm-pieces and adjustably secured to the extension of the arm-piece, substantially as 40 specified.

In testimony whereof I have signed my name to this specification in the presence of two subscribing witnesses.

HARRY C. WILSON.
